US0D1063777S

(12) **United States Design Patent** (10) **Patent No.:** **US D1,063,777 S**
(45) **Date of Patent:** **** Feb. 25, 2025**

(54) **VEHICLE WHEEL, TOY VEHICLE WHEEL,
AND/OR REPLICAS THEREOF**

(71) Applicant: **Bayerische Motoren Werke
Aktiengesellschaft**, Munich (DE)

(72) Inventor: **Dinko Kraljevic**, Munich (DE)

(73) Assignee: **Bayerische Motoren Werke
Aktiengesellschaft**, Munich (DE)

(**) Term: **15 Years**

(21) Appl. No.: **29/900,961**

(22) Filed: **Aug. 28, 2023**

(30) **Foreign Application Priority Data**

Mar. 1, 2023 (DE) 402023100111.0
